UNITED STATES PATENT OFFICE.

JACOB BERMAN, OF NEW YORK, N. Y.

LUGGAGE CARRIER.

Application filed September 24, 1923. Serial No. 664,507.

The main object of this invention is to provide a luggage carrier primarily designed for use with automobiles and which is collapsible perpendicularly so as to occupy a relatively small amount of space when not in use.

Another object is to provide a device as mentioned having a tool box and a roll curtain serving as a cover for protection of the articles stored in the carrier.

These and other objects will become apparent in the description below, in which characters of reference refer to like-named parts in the drawing.

Referring briefly to the drawing, Figure 1 is a front elevational view of the luggage carrier fully extended.

Figure 2 is an end elevational view of the same.

Figure 3 is a cross sectional plan view taken on line 3—3 of Figure 1.

Figure 4 is a bottom plan view of the luggage carrier cover, showing the extensible doors in folded position.

Figure 5 is a view of an automobile, showing the luggage carrier mounted thereon and in collapsed position.

Figure 6 is a fragmentary end elevational view of the upper end of the luggage carrier, showing the position the folding doors assume when adding additional storage space to the luggage carrier.

Figure 7 is a front elevational view of the device by which the luggage carrier is rigidly held when extended.

Figure 8 is a fragmentary elevational view of a portion of the luggage carrier and shows the means for locking the extended luggage carrier to the device illustrated in Figure 7.

Referring in detail to the drawing, the numeral 10 indicates the front wall of a casing whose side walls 11 are integral therewith. Said casing is provided with a floor 12 upon which the walls of a box 13 are mounted, the box having a cover 14 hinged thereto. The box may be divided into any number of compartments and serves as a suitable receptacle for tools and the like. A plurality of rectangular bands 15, 15^a, and a similar upper band 16, are connected to each other in such manner that one band is superposed above the next successive band. The end portions of the bands are connected by levers 17, said levers being hinged to each other and folding in

one direction only. The long sides 18 of the bands are provided near their ends with slots 19 in which pins 20 are engaged, the pins being fixed to the upper ends of the lazy tongs 21. A pair of lazy tongs 22 are fixed to the long side 18 of the upper band 16 which crosses the lazy tongs 21 intermediate their length, the lower ends of the lazy tongs 22 having pins which engage in the slots 19 of the band immediately below the band 16. The lower ends of the lazy tongs 23 are fixed centrally on the wall 10 of the casing and are provided at their upper ends with pins which are engaged in the slots 19 of the lowest band 15. Lazy tongs 24 are mounted similarly to the lazy tongs 21, as above mentioned. Sleeves 25 slidable on the band 15^a have the adjacent ends of the lazy tongs 21 and 24 secured thereto. The long side 18 of the band 15^a is provided with a plurality of spaced-apart detents 26, the purpose for which will be more fully hereinafter described. The lower ends of the lazy tongs 24 are slidable in a slot in angle irons 27, the latter being fixed to the floor 12 of the casing. Vertical braces 28 whose lower ends are fixed to the lower end of the lazy tongs 24, rise vertically when the carrier is in extended position and are secured to the sleeves 25 by a thumb screw 29, said thumb screw being threaded into one wall of the sleeves and adapted to engage any of the detents 26. Similar braces 30 have their upper ends secured to the upper ends of the lazy tongs 21, the lower ends extending vertically and being secured to their respective thumb screws 29 in a manner similar to the braces 28.

The sides 18 of the upper band 16 have hinges 31 secured thereto by which means a cover 32 is mounted on the device. Hasps 32^a are hingedly attached to the ends of the cover and when the device is fully collapsed, receive the staples 33 in suitable slots in said hasps. Latticed doors 34 are hingedly secured to the underside of the cover 32 and when in the position shown in Figure 4, are not used, said doors being retained flush upon the surface of the cover by members 35. The lower ends of the sides 36 are provided with slits 37 which engage a pin 38 and a thumb screw 39 when the doors 34 are swung at right angles to the cover 32, said pin and thumb screw projecting from the end portions of the upper band 16. The

pin 38 is an extension of a bar which spans the distance between the ends of the bands 16 and is secured in place by the thumb screw 39. Said bar has the free end of a 5 canvas curtain 40 secured thereto, the opposite end of said curtain being trained upon a shade roller 41, the shade roller being mounted between brackets 42 located on the floor 12 of the casing.

10 The long side 43 of the upper band 16 has a notch 44 formed therein intermediate its length. This notch engages a pin 45, said pin being mounted on a slide bar 46. The latter is slidable in a hollow tubing 47 securely fixed to the side of the automobile 48 by passing screws thru the holes 49 in the ears 50. The bar 46 is provided with a plurality of spaced apart openings 51 in which a flange 52 engages. Said flange 52 is fixed to the free end of a resilient spring 53, the upper end of the latter being secured to the tubing 47. A rod 54 is slidably mounted below block 55, the latter projecting from the side of the tubing 47. The lower end 25 of the rod has a handle 55, and the upper end is provided with a cam block 56 in which a slit 57 is formed. A long plate 58 is slidably mounted on member 43 and is provided with a notch 59 similar to 44, the axis of the notch 59 being at right angles to the axis of the notch 44. An ear 60, integral with the plate 58, engages the cover 32 when the device is completely collapsed as in the position shown in Figure 5.

30 The method employed in using the luggage carrier is as follows. Normally the cover 32 is rigidly fastened to the casing 10 by the ear 16 which operates in a slot of said cover. The hasps 32^a also serve as a means for locking the cover in collapsed position on the casing. To make the device ready for the reception of luggage such as valises or the like, the hasps 32^a are disengaged from the staple 33 and the ear 60 is slid in the direction indicated in Figure 8. Before sliding this ear in said direction, however, the handle 61 is grasped and the cover 32 is pulled upwardly. In this manner the bands 15, 15^a, and 16, are moved into spaced-apart relation, one above the other, and the lazy tongs 21, 22, 23, and 24, are extended angularly. The movement of said lazy tongs from the horizontal to the angular position is permitted thru the medium of the slots 19 in the bands. The side levers 17 are likewise extended into the position shown in Figure 2. The braces 28 and 30 are also changed from a substantially horizontal position, assumed 55 when the carrier is collapsed, to a vertical position when said carrier is fully extended. The thumb screws 29, by passing thru the adjacent ends of the braces 28 and 30, and the sleeves 25, will engage the nearest detent 26 and retain the front portion of the

luggage carrier in fully extended position. When said carrier has been secured in extended position, the rear portion of the bands not supported by the lazy tongs, remains rather shaky. To introduce rigidity to this 70 side of the luggage carrier, the device illustrated in Figure 7 is used. As previously stated, this device is secured to the tonneau of the automobile, and the bar 46 is slid into a position where the pin 45 will engage in 75 the notch 44, said notch being formed in the upper band 16, the pin 52 meanwhile engaging the corresponding opening 51. In order to lock the luggage carrier to member 43, the plate 58 is slid in the direction indicated by the arrow in Figure 8. This causes the notch 59 in said plate 58 to engage member 43 at a different plane and thereby lock the upper band 16 rigidly to the side of the automobile thru the medium of the device 80 illustrated in Figure 7. The chamber formed within these bands is then ready to receive the luggage, the latter being concealed from view by the curtain 40 which is automatically unfurled from the roll 41 when the device is extended. When additional space is required, the cover 32 is rotated into substantially vertical position, and the doors 34 are rotated about their hinges until the slots 37 in the ends of said doors engage 90 respectively the pin 28 and the thumb screw 39. By securing the doors 34 in place in this manner, an additional compartment of the luggage carrier is formed on top of the band 16, but the cover 32 in this position does not protect the luggage as it forms a side wall when so locked. In order to cover and protect the luggage when the cover 32 is 95 in vertical position, the curtain 40 is disengaged from the band 16 and further unfurled until it partly envelops the luggage and assumes the position indicated in Figure 6.

I claim:—

1. A luggage carrier comprising a casing, a cover on said casing, a plurality of U-shaped bands beneath said cover, said bands being arranged one above the other, pivoted levers connecting the ends of said bands, lazy tongs connected to said bands, means for extending the cover above the casing, and means for collapsing the same. 110

2. A luggage carrier comprising a casing, a plurality of U-shaped bands normally housed in said casing, a cover, said cover being hingedly connected to the upper band, levers connecting the end portions of said bands, lazy tongs connecting said bands, and means for locking the lazy tongs and cover in extended position. 120

3. A luggage carrier comprising a casing, a cover for said casing, a plurality of U-shaped bands normally housed in said casing and retained one above the other, the upper band being hingedly connected to the cover, sleeves slidable on an intermediate 125 130

band, braces connecting the outer ends of the lazy tongs with the sleeves, said sleeves when urged toward the ends of said bands being adapted to extend the cover above the casing, and means for locking the sleeves in extended position.

4. A luggage carrier comprising a casing, a cover on said casing, a tool box in said casing, a plurality of slotted U-shaped bands arranged side by side beneath said cover, lazy tongs having their ends engaged in the slots of said bands, sleeves slideable on an intermediate band, said intermediate band having spaced-apart detents thereon, the central intersecting ends of said lazy tongs being secured to the sleeves, braces, the adjacent ends of said braces connected to the sleeves, the outer ends of said braces engaging the outer ends of the lazy tongs, thumb screws securing said braces to the sleeves and engageable in the detents of the intermediate band, said thumb screws when engaging the detents being adapted to lock the cover and bands in extended position, and means for covering the chamber within the luggage carrier.

5. A luggage carrier comprising a casing, a tool box in said casing, a plurality of slotted U-shaped bands positioned one above the other and adapted to fold into the casing, lazy tongs connecting said bands, means for retaining the bands in extended position, a cover hingedly secured to the upper band, a roller mounted in said casing, a curtain about said roller, the outer end of the curtain being secured to the upper band, means for supporting the bands when in extended position, and means for retaining the cover when said device is extended.

40 6. A luggage carrier comprising a casing, tool box in said casing, a plurality of slotted U-shaped bands positioned one above the other and adapted to fold into the casing, lazy tongs connecting said bands, means

for retaining the bands in extended position, 45 a cover hingedly secured to the upper band, a roller mounted in said casing, a curtain about said roller, the outer end of the curtain being secured to the upper band, latticed doors hingedly secured to the underside of the cover, said cover when raised vertically permitting the doors to be rotated thereby adding additional volume to luggage carrier, the free ends of said doors engaging projections on the upper bands, 50 55 and means for supporting the device when fully extended.

7. A luggage carrier comprising a casing, a tool box in said casing, a plurality of slotted U-shaped bands positioned one above 60 the other and adapted to fold into the casing, lazy tongs connecting said bands, means for retaining the bands in extended position, a cover hingedly secured to the upper band, a roller mounted in said casing, a curtain trained on said roller, the outer end of the curtain being secured to the upper band, latticed doors hingedly secured to the underside of the cover, said cover when raised vertically permitting the doors to be 65 70 rotated thereby adding additional volume to the luggage carrier, the free ends of said doors engaging projections on the upper bands, a tubing mounted adjacent the device, a bar slideable in said tubing and having openings therein, a resilient plunger mounted on said tubing and engageable with any of said openings, a pin on the lower end of said bar engageable with the upper band of the luggage carrier, said bar being adapted to support the luggage carrier in extended position, and means for releasing said bar from the band of the luggage carrier.

Signed at New York, in the county of 85 New York, and State of New York, August, A. D. 1923.

JACOB BERMAN.
